EXPANDER FOR PISTON SKIRTS

Walter J. Six, Indianapolis, Ind.

Application January 14, 1935, Serial No. 1,632

5 Claims. (Cl. 309—12)

This invention relates to an expander for a piston skirt adapted for use in the cylinders of internal combustion engines, compression engines, steam engines and the like, and of the general character shown and described in my Letters Patent 1,958,154, issued May 8, 1934.

It is the purpose of this invention to provide an expander of this general character in sections so as to render it easy to install and permit of adjustability in respect to the expansive forces exerted thereby. Such an expander may be of the character which completely encircles the interior of the skirt with apertures in the boss sections which encircle the bosses either freely so as not to engage therewith, or engages and bears directly upon the side surfaces of the bosses. On the other hand, the expander may be of that character which lies only upon one side of the boss to be yieldingly wedged between the skirt and the sides of the bosses. The boss sections may or may not press against the boss or boss portions which include the struts and the expander may comprise from two to six sections.

The particular feature of the invention resides in forming the expander of a plurality of sections having therein edges abutting when assembled, and which may be formed on a bias to permit of a wedging action, thereby being adjustable so as to obtain the desired expansive pressure exerted upon the inside wall of the skirt.

Other objects and features of the invention will be understood from the accompanying drawing and the following description and claims:

Fig. 1 is a plan view of half the underside of a piston showing the split side thereof with one form of the expander mounted therein. Fig. 2 is a section taken on the lines 2—2 of Fig. 1. Fig. 3 is the same as Fig. 2 illustrating the method of installation of the expander. Fig. 4 is a perspective view showing a portion of the expander. Fig. 5 is a plan view taken on the line 5—5 of Fig. 4. Fig. 6 is the same as Fig. 4 showing a modified form. Fig. 7 is a plan view taken on the line 7—7 of Fig. 6. Fig. 8 is a diagrammatical illustration of different arrangements of the expander in the piston.

In the drawing, one type of piston is shown for illustration having the usual head 10, ring grooves 11, lands 12 and a skirt 13. Immediately beneath the piston ring grooves there are cut a pair of slotted openings 14 which extend partly about the circumference of the piston and serve to increase the flexibility of the skirt. The skirt 13, as herein illustrated, is split by a slightly diagonal but substantially vertical cut 15 extending

from the bottom of the skirt into one of the slotted openings 14. The skirt 13 usually carries struts 16 which support the projections formed by piston pin bosses 17. However, the particular character of the piston forms no part of the invention other than to be acted upon by the expander as, and for the purpose well known in the art.

The expander in one embodiment of the invention comprises essentially a pair of boss sections 18, each of which is provided with an aperture 19 adapted to encircle the bosses 17 or a corresponding concave edge adapted to bear against and embrace a portion of the side surface of the bosses 17.

The section 18 may be considered as providing a support in which the expander proper is adjustably positioned to the extent of the expanding pressure desired. The expander 20, substantially of the character illustrated in the above-mentioned patent, comprises a shell curved in cross section and provided, intermediate its edges and extending longitudinally and substantially centrally thereof, with a fold or expansion formation 21 adapted to partially span the slot 15 of the piston skirt.

As shown in the diagrammatical illustrations in Fig. 8, various arrangements of the expander may be employed wherein the boss sections may span and encircle the bosses as shown in Figs. A and B with the expander sections mounted on opposite sides thereof so as to exert pressure between opposite sides of the piston. The expander sections may, on the other hand, only embrace a portion of the bosses to exert pressure between the wall of the piston and the bosses, as shown in Fig. C. It will be noted that the expander of Fig. A is of four sections; that of Fig. B of two sections; while that of Fig. C is of six sections.

The boss sections 18 have their forward edge stamped with a folded S-curve to provide a longitudinal recess for the reception of the adjacent edge of the expander section, said recessed edge being indicated at 22. As illustrated herein, said recessed edge is biased, extending slightly at an angle approaching the walls of the piston toward the top. The free side edges of the expander section 20 are correspondingly biased to extend at the same angle when in operative position. Thus, the opposite side edges of the expander section 20 are adapted to slide and be embraced within the recessed edges 22 of the boss section. The upper corner of the expander section is provided with a tooth-like projection 23 so positioned as

to extend over the top edge of the boss section and lock thereon as indicated in Figs. 2, 4 and 5. However, there may be formed in the recessed edge of the boss section adjacent the top thereof 5 one or more perforations 24 for reception of and interlocking with projection 23 when it is determined for proper expansion pressure that the expander section may not be positioned so as to extend the full length of the boss section.

10 In the modified forms illustrated in Figs. 6 and 7, in lieu of the folded recessed edge 22, there may be provided a recess 122 in the expander sections 118 formed by securing side plates 125 thereon by rivets 126. The adjacent and abutting edges of the expander section 120 and the boss section 118 may be formed with a plurality of toothed projections 123 in saw-tooth formation 15 to permit the expander section to be slid upwardly with respect to the boss section and piston 20 but be interlocked therewith to permit downward movement.

From the foregoing, it will be noted that in any of the arrangements of the expanders as suggested by the illustrations of Fig. 8, or in the modified forms herein referred to, installation 25 of the expander will be simplified. Thus, the boss section is first mounted within the piston and held in place about or against the piston pin bosses whereupon the expander section may be inserted from the underside of the piston so 30 as to bear between the piston wall and have its edges engaged in the recessed edges of the boss section in the manner illustrated in Fig. 3. By tapping the lower end of the expander section, it may be forced and wedged upwardly until 35 the desired expanding pressure is attained to cause the desired expansion of the piston skirt. Depending upon the relative position of the expander section in respect to the boss section and skirt, and within limits, various pressures and 40 expansions may be readily obtained. The invention, therefore, contemplates a piston expanding structure which provides easy installation and control over the expanding force exerted upon 45 the piston, and, therefore, the amount of expansion of the piston skirt.

The invention claimed is:

1. The combination with a piston having a skirt and piston pin boss portions, of a piston 50 skirt expander comprising boss sections associated with the piston pin boss portions, an expander section removably associated with said boss sections mounted under spring tension between said sections and the piston skirt for exerting an expansive pressure thereagainst, abutting edges of said sections extending upwardly 55 at an angle away from the plane through the center of the piston and boss axes, and means formed thereon to permit slidable interlocking thereof, whereby the yielding pressure of the expander section against the piston skirt will be increased as it approaches alignment with the boss section.

2. The combination with a piston having a 60 skirt and piston pin boss portions, of a piston skirt expander comprising boss sections associated with the piston pin boss portions, an expander section removably associated with said boss sections mounted under spring tension be-

tween said sections and the piston skirt for exerting an expansive pressure thereagainst, and a plurality of ratchet teeth formed along the abutting edge of one of said members arranged to permit relative sliding movement therebetween when inserting the expander section in place while interlocking to prevent disengagement thereof.

3. The combination with a piston having a skirt and piston pin boss portion, of a piston 10 skirt expander comprising boss sections adapted to interlock with the piston pin boss portions, each of said sections having a grooved edge extending at an angle to the vertical axis thereof and sloping from the upper portion toward the 15 lower portion of the piston, and an expander section formed of sheet metal and having an expansive formation therein provided with free edges extending at an angle corresponding to the grooved edges of the boss sections for slidable 20 engagement therein, said expander section being slidably upwardly within the piston so as to be wedged and compressed under its inherent spring tension between the skirt and boss sections, its compression being increased as it is forced up- 25 wardly into expanding position.

4. The combination with a piston having a skirt and piston pin boss portion, of a piston skirt expander comprising boss sections adapted to interlock with the piston pin boss portions, 30 each of said sections having a grooved edge extending at an angle to the vertical axis thereof and sloping from the upper portion toward the lower portion of the piston, an expander section formed of sheet metal and having an expansive 35 formation therein provided with free edges extending at an angle corresponding to the grooved edges of the boss sections for slidable engagement therein, said expander section being slidably upwardly within the piston so as to be 40 wedged and compressed under its inherent spring tension between the skirt and boss sections, its compression being increased as it is forced upwardly into expanding position, and means on the adjacent edges of said sections for interlock- 45 ing with the other sections to prevent the releasing thereof.

5. The combination with a piston having a skirt and piston pin boss portion, of a piston skirt expander comprising boss sections adapted to interlock with the piston pin boss portions, 50 each of said sections having a grooved edge extending at an angle to the vertical axis thereof and sloping from the upper portion toward the lower portion of the piston, an expander section 55 formed of sheet metal and having an expansive formation therein provided with free edges extending at an angle corresponding to the grooved edges of the boss sections for slidable engagement therein, said expander section being slidably upwardly within the piston so as to be 60 wedged and compressed under its inherent spring tension between the skirt and boss sections, its compression being increased as it is forced upwardly into expanding position, and a plurality of 65 protruding saw teeth provided on the abutting edge of one of said sections for interlocking with the other sections to prevent the release thereof.
